D10-37. OR D 12,774 EX

UNITED STATES PATENT OFFICE.

EUGENE F. MARGOT, OF BOSTON, MASSACHUSETTS.

DESIGN FOR A WATCH-CASE.

SPECIFICATION forming part of Design No. 12,774, dated February 21, 1882.

Application filed January 12, 1882. Term of patent 7 years.

To all whom it may concern:

Be it known that I, EUGENE F. MARGOT, of Boston, in the county of Suffolk and State of Massachusetts, have originated and produced 5 a new and ornamental Design for Watch-Cases and Similar Articles, of which the following is a full, clear, and exact description, reference being had to the accompanying photographic illustration, making part of this specification.

10 A represents the back and front sides of the case, which may be left plain or ornamented, as desired.

The edge of the case to which my design is adapted consists of the main central bead, ornamented as shown, or with any design adapted thereto as heretofore employed. At each side of this central bead is formed a plain narrow band or flat surface, T, and joined by a narrow right-angle plain surface, S, and then adjoining,

20 ing which is formed a pearl bead, R, adjoining a very narrow plain flat band or surface, P, and then a very narrow right-angle surface, N, and connecting with another narrow plain flat sur-

face, V, then the usual incline or bevels reaching to the back and front of the case, there being two narrow or plain flat surfaces T, and two narrow right-angle surfaces, S, and two pearl beads, R, and two very narrow right-angle surfaces, N, and two narrow plain flat surfaces, V, all being arranged in the relative positions 25 30 shown in the photographic illustrations, the whole forming a design for the edge of a watch-case.

I claim—

The design for the edge of a watch-case, 35 consisting of the two narrow plain flat surfaces T T, the two right-angle plain surfaces S S, the two pearl beads R R, the two plain flat surfaces P P, the two right-angle surfaces N N, and the two plain flat surfaces V V, arranged at each side of the main central bead, 40 as herein shown and described.

EUGENE F. MARGOT.
